UNITED STATES PATENT OFFICE.

FRED MERDIAN, OF VANCOUVER, WASHINGTON.

VALVE GRINDER.

Application filed September 13, 1922. Serial No. 587,977.

To all whom it may concern:

Be it known that I, FRED MERDIAN, a citizen of the United States, residing at Vancouver, in the county of Clarke and State of Washington, have invented certain new and useful Improvements in Valve Grinders, of which the following is a specification, reference being had to the accompanying drawings.

10 This invention relates to improvements in valve grinders, and more particularly to a device of this character adapted to simultaneously grind a plurality of valves.

An important object of the invention is to provide a device of this character which may be applied directly to the cylinder of an internal combustion engine and secured thereto to grind the valves in position.

Another object of the invention is to provide a device of this character wherein the shifting of the valve upon its seat is automatically accomplished by the operation of the machine.

A further object of the invention is to provide in a device of this character having grinding means for grinding a plurality of valves at the same time, means whereby the valves are successively lifted and allowed to impinge against their seats in a slightly shifted position.

A still further object of the invention is to provide a device of this character in which the grinding and controlling mechanism is compactly arranged and so constructed that it may be readily handled without danger of disarranging the same.

An additional object of the invention is to provide a device of this character which is simple in its construction and arrangement, durable in service, and a general improvement in the art.

The invention further consists in the details and arrangement of the mechanism as shown in the accompanying drawings, in which:—

Figure 1 is a plan view of a valve grinding mechanism constructed in accordance with my invention;

Figure 2 is a front elevation thereof;

Figure 3 is a section on the line 3—3 of Figure 1;

Figure 4 is a section on the line 4—4 of Figure 1; and

Figure 5 is a section on the line 5—5 of Figure 1.

Figure 6 is a fragmentary enlarged elevation, the plate 25 being removed and parts being broken away.

Referring now more particularly to the drawings, the numeral 10 designates a base plate which is substantially rectangular and which is provided in one side thereof with a cut-out portion 11. The plate is provided upon its under surface with a lug 12 adapted to engage in the head bolt opening 13 of the engine cylinder block 14 with which the grinding device is to be employed. The base plate is further provided with an opening 15 adapted to align with the second head bolt opening 13 for the reception of a securing bolt 16 so that the plate may be rigidly secured to the head of the engine. Extending upwardly from the base plate at opposite ends thereof are end bearing plates 17 and 18, and intermediate these plates and at the forward side of the cut-out 11 from the bearing plate 17 is a third or intermediate bearing plate 19.

The bearing plate 18 is provided at what may be designated the rear end thereof with an extension 20 forming a bracket coacting with a bracket 21 secured to and extending upwardly and rearwardly from the plate 10 intermediate the bearing plates 17 and 19. These brackets form a support for a motor base plate 22 upon which a motor 23 may be mounted for a purpose hereinafter to appear. A brace 24 extends intermediate the bearing plates 17 and 19 and is secured to each thereof and to the bracket 21 tending to hold these plates rigidly in position. The ends of the bearing plates 18 and 19 are connected by end plates 25 and 26 which combine with the bearing plates 18 and 19 to form a gear box in which the operating mechanism of the device is contained.

The numeral 27 designates spaced guide plates extending intermediate the bearings 17 and 19 and having their ends mounted in sockets 28 formed in the adjacent faces of these bearing plates. The guide plates are arranged above the cutout portion 11 and

have formed therein at spaced intervals aligned openings 29 receiving the hubs 30 of pinions 31. Each pinion 31 has formed therein a bore 32 through which is directed a shaft 33 having a slot 34 formed therein. Extending through these slots and engaging in the hubs of the pinions 31 are retaining pins 35 which by their engagement in the slots limit the movement of the shafts 33 5 with relation to the pinions 31 as regards endwise movement of the shaft and prevent relative rotation of the pinion and shaft. The lower ends of the shafts 33 are provided with heads 36 having upon their lower 10 faces valve engaging elements 37 adapted to engage in the sockets formed in the valve for engagement with a grinding tool. The upper end of each of the shafts 33 is externally screw-threaded and is further provided with a bore 40 opening through such upper end which is screw-threaded. A head 38 is provided having a threaded bore in its lower end engaging the upper end of the stem, and an opening formed in its 15 upper end for the reception of a set screw 39 engaging in the bore 40 of the stem. This head may be adjusted upon the stem and locked in adjusted position by means of the set screw for a purpose presently to 20 appear. Between the lower guide plate 27 and the upper face of the head 36 a spring 33' is disposed which surrounds the shaft 33 and which forces the same downwardly so as to normally maintain the upper end 25 of the slot 34 in engagement with the pin 35. Slidably and rotatably mounted in the bearing plates 17 and 19 is a shaft 41 having formed thereon worms 42 engaging the pinions 31. The end portion of the shaft 40 41 projects into the gear box and has secured thereto within the gear box a pinion 43 and a collar 44 having a yoke receiving groove 45, the collar 44 in the present instance being shown as formed integrally with the pinion 43. The pinion 43 meshes with a gear 46 secured to the shaft 47 having its ends mounted in the end plates 25 and 26. This shaft has mounted thereon a wiper cam 48 operating between rigid arms 49 secured to a shaft 50 having its ends slidably mounted in the bearing plates 18 and 19. This shaft has secured thereto a shifter fork 51 engaging in the groove 45 of the collar 44. It will be seen that when the shaft 47 is rotated the shaft 41 will be simultaneously rotated and reciprocated, the design of the gear 46 and pinion 43 being such that they remain in mesh during the shifting of the shaft. 50 A cam shaft 52 having cams 53 mounted thereon corresponding in number and arrangement to the shafts 33 is mounted in the bearing plates 17, 18 and 19 for rotation, the shaft 52 being parallel to the guide plates 27 and shaft 41. That portion of the shaft 52 disposed within the gear box has secured thereto a spiral gear 54 meshing with a pinion 55 mounted upon the shaft 47 and is further provided with a gear 56 meshing with a pinion 57 carried by a shaft 58. The shaft is rotatably mounted in the bearing plates 18 and 19 and has one end thereof extending through the bearing plates and provided with a drive pulley 59 adapted to be connected with a drive pulley 60 upon the shaft of the motor 23 by a belt 61. It is to be here stated that the motor and the driving connections between the motor and shaft 58 are merely illustrated since any desired source of power 70 may be employed and any means may be provided for connecting the source of power to the shaft 58. Intermediate the guide plates 27 and the cam shaft 52 and parallel to each thereof is a bearing shaft 62 mounted in the bearing plates 17 and 19 and having mounted thereon rocker arms 63 corresponding in number and arrangement to the shafts 33 and cams 53. The shaft engaging end of the rocker arm 63 is furcated, as 75 indicated at 64, to receive therebetween the shank of the head 38, the arms formed by the furcation being provided with upstanding end portions 65 engaging beneath the flange 38' of the head. The cam engaging 80 ends 66 of the rocker arms extend in the path of the cams 53 but are so disposed as to clear the shaft 52. The wiping face 67 of the cams 53 terminates in an abrupt shoulder 68 which suddenly releases the 85 rocker arms 63 to permit the shaft 33 to be forced downwardly by its spring with a snap motion. 90 In the use of my device, the same is secured to the cylinder upon which the valves 95 are to be ground by attaching the base plate by means hereinbefore described. When properly applied, the shafts 33, and more particularly the heads 36 thereof will each be arranged directly over a valve 69 of the 100 block 14. Prior to the placement of the mechanism, a light spring 70 having just sufficient strength to lift the valve 69 from its seat is placed about the stem 71 of the valve and within the valve pocket 72. These 105 springs 70 will be of less strength than the springs 33' for reasons hereinafter to appear. A valve grinding compound having been placed between the valve 69 and seat 73 thereof, the motor or other source of power is thrown into operation. The drive from the motor is transmitted to the shafts 52 and 47, the rotation of the latter having the effect of simultaneously rotating and reciprocating the shaft 41, this shaft being 110 continuously rotated in the same direction. The rotation of the shaft 41 causes the pinions 31 to be rotated in a given direction at a given speed and accordingly the shafts 33 are likewise rotated in conjunction with 115 120 125 130

this rotation. Rotation in opposite directions is applied to the pinions 31 and shafts 33 by the reciprocation of the shaft 41, this shaft during its reciprocation acting as a 5 rack engaging the pinions and causing such alternate rotation. This rotation in opposite directions taken in conjunction with a continuous rotation in one direction results in an advancing movement of the shaft 33. 10 Since the rotation imparted to the pinion by the rotation of the shaft is, during movement of the shaft in one direction, added to the rotation imparted by such movement and during the movement of the shaft in 15 the opposite direction subtracted therefrom, the valve 69 will accordingly be continuously oscillated, the oscillation in one direction being of less length than the oscillation in the opposite direction. This motion 20 may, for the purpose of identification, be termed "progressive oscillation". At the same time the rotation of the shaft 52 brings the cams 53 into engagement with the rocker arms causing the shafts 33 to be 25 elevated and permitting the valve 69 to leave its seat under the pressure of the spring 70. Since the valve is continually in movement, the valve will be rotated while held from its seat and will be engaged with 30 the seat at a new spot and the valve grinding compound accordingly shifted and prevented from bunching and pocketing. As the cam leaves the rocker arm, the same is released permitting the shaft 33 to move downwardly smartly under the action of spring 33', reseating the valve with a snap action similar to the action of the valve in seating during operation of the engine. The extent or strength of the blow applied by the 40 valve in engaging its seat may be regulated by adjusting the head 38 so as to shorten the length of movement of the shaft 33 under influence of the cam 53. In actual use it has been found that the application of 45 the snap action in returning the valves to their seats results in a much more perfectly ground seat than is possible in the ordinary manner of valve grinding where the valve is permitted to leave its seat and simply 50 return to its seat by pressure or the weight of the tool with which the grinding is being done. Furthermore, since a plurality of valves may be simultaneously ground and similar movements are applied to each 55 thereof, all of the valves will be ground in approximately the same length of time, resulting in the completion of the valve grinding operation for the number of valves which the machine is adapted to grind, four 60 in the present instance, in the same time that it would ordinarily require to grind a single valve.

While the construction hereinbefore described and illustrated is particularly adapted for use with a particular style of en-

gine, the principle disclosed is applicable to grinding the valves of practically all engines where the valves are seated directly in either the head or cylinder block of an engine having a removable head. It is believed to be 70 obvious that a construction such as hereinbefore described will result in a material saving of time in grinding the valves and at the same time the valves will be ground 75 with a mechanical precision impossible where hand-operated machines are employed. It will furthermore be obvious that the construction hereinbefore described and shown in the accompanying drawings is 80 capable of many changes and modifications without materially departing from the spirit of my invention, and I accordingly do not limit myself to such specific structure except as hereinafter claimed.

I claim:—

1. In valve grinding mechanism, a valve engaging element, and means for continuously oscillating the element and rotatably advancing the same in a given direction, including a pinion operatively connected with the valve engaging element, a worm engaging said pinion, and means for simultaneously reciprocating the worm and rotating the same in a given direction.

2. In valve grinding mechanism, a plurality of shafts each provided with a valve engaging head, pinions on said shafts, a worm engaging said pinions, and means for simultaneously rotating and reciprocating said worm.

3. In valve grinding mechanism, a shaft provided with a valve engaging head, a pinion on said shaft, a worm engaging said pinion, a second shaft, drive gearing connecting said shaft and said worm, and means operated from said second shaft for reciprocating said worm.

4. In valve grinding mechanism, a shaft provided with a valve engaging head, a pinion on said shaft, a worm engaging said pinion, a second shaft, drive gearing connecting said shaft and said worm, means operated from said second shaft for reciprocating said worm, including a cam carried by said second shaft, a third shaft, arms carried by said shaft and arranged in the path of said cam, and a connection between said third shaft and worm whereby the worm is reciprocated in conjunction with said third shaft.

5. In valve grinding mechanism, a shaft, a valve engaging head carried thereby, a spring normally forcing the head in one direction, means for withdrawing the head and subsequently suddenly releasing the same, and means for progressively rotating the shaft including a pinion carried by the shaft and through which the shaft is longitudinally shiftable, a worm engaged with the pinion, and means for simultaneously rotating and reciprocating said worm.

6. In valve grinding mechanism, a shaft provided with a valve engaging head, a pinion on said shaft, a worm engaging said pinion, a second shaft, drive gearing connecting said shaft and said worm, means operated by said second shaft for reciprocating said worm including a cam carried by said second shaft, abutment members disposed in the path of

said cam upon opposite sides of said second shaft, and means operated by said abutment members and engaging said worm whereby the worm is reciprocated in conjunction with the abutment members. 10

In testimony whereof I hereunto affix my signature.

FRED MERDIAN.
